UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

1,337,782.

Specification of Letters Patent. Patented Apr. 20, 1920.

Application filed May 17, 1918. Serial No. 235,090.

To all whom it may concern:

Be it known that I, ALBEN E. LUNDELL, a citizen of the United States, residing at New York, in the county of Bronx, State 5 of New York, have invented certain new and useful Improvements in Telephone-Exchange Systems, of which the following is a full, clear, concise, and exact description.

10 This invention relates to improvements in telephone exchange systems, and more particularly to improvements in telephone systems in which means are provided for indicating the designation or character of calling lines.

15 The object of the present invention is to simplify the apparatus and circuit arrangement employed to control the establishment of connections between calling and called

20 lines.

To attain this object, according to this invention, the switching means by which telephonic connections are established is controlled in its operation by a switch operated in accordance with the character or 25 designation of the calling line. This switch is preferably of the well-known sequence switch type, although circuit controlling devices of a widely varying character may 30 be employed without departing from the spirit of the invention. Depending on the character or designation of the calling line, a certain predetermined number of impulses are sent to an impulse receiving device, such as a set of counting relays. The 35 impulse receiving device operates the switch in a manner characteristic for the line calling. The various operations of the switch will determine the manner in which the 40 calling line should be charged for the service. In view of the fact that this same switch is utilized for controlling the interconnection of the calling and called lines, controlling devices, such as relays, that 45 were heretofore used for this purpose will be saved.

Obviously, instead of the specific apparatus and circuits disclosed, other devices well known in the art may be employed in 50 practising this invention. The invention is applicable also to semi-automatic telephone systems in which switching means, differing from those (calling plug and sequence switch) exemplified in the herein disclosed 55 embodiments of the invention, are used.

The various features of the invention will more clearly appear from the following description of the preferred embodiment of this invention, and the appended claims.

Figure 1 illustrates three telephone lines 60 with their central office terminal connections and identifying circuits; Fig. 2 illustrates a line finder and cord finder circuit for extending a calling line, Figs. 3, 4 and 5 illustrate a cord circuit terminating in a 65 plug, a called line terminating in a spring jack into which the plug may be inserted, and a part of the operator's circuit; Fig. 6 illustrates the part of the operator's circuit that has to do with determining the identity 70 of a calling line with respect to its class of service; and Figs. 7, 8, 9 and 10 show details of the common identifying device or commutator and its connections.

In the particular embodiment of the invention illustrated in the accompanying drawings, I have shown three lines adapted for different classes of service extending from their respective stations 100, 101 and 102 to switch terminals at the central office. 75 100 may be assumed to be a private branch exchange message-rate station, 101 a party line coin-collector station, and 102 an individual flat rate station. The character and arrangement of apparatus at such stations 80 is well known, and I have not thought it necessary to illustrate it specifically. Cut-off relays 103, 104, 105 and line relays 106, 107, 108 are associated with the three lines 85 in the usual way. The line from station 100 90 being a message rate line, also has associated with it at the central office a message register 209.

Each of the lines has four conductors, 95 two being the ordinary line conductors, and the other two, 110 and 111, being conductors local to the exchange. The local conductor 110 of each line has included in it a winding of the associated cutoff relay, while the conductor 111 in each case extends to the 100 common identifying device or apparatus for producing the characteristic electrical conditions which serve to identify the various lines. This device is represented diagrammatically at 112 in the drawing, and 105 is illustrated as comprising nine paths extending from the free pole of the central battery to nine terminals which are common to the lines of the exchange, and to one or another of which the conductor 111 110

of each line circuit is extended, depending upon its class of service. I shall herein-after particularly describe the type of identifying apparatus which I have found it convenient to employ. For the present, it is sufficient to say that this apparatus is arranged continuously to modify current that may flow in each of the paths so as to produce trains of impulses, the impulses of each train being divided into groups and subgroups and the number of impulses in each group and subgroup being varied so as to produce different and characteristic combinations. The duration of the groups and subgroups in each train is determined and limited by pick-up impulses. Each of the subgroups consists of one or more impulses of current, as determined by the action of circuit changing contacts in the various paths. A single interruption in one of the subgroup periods divides the current flow in that period into two impulses, and two interruptions in the subgroup period divides the current flow in that period into three current impulses. To meet the requirements of the present embodiment of my invention, I have found it only necessary to provide a maximum of three impulses in each subgroup period, the various combinations of one, two or three impulses in each subgroup of a group affording nine different characteristic combinations of current impulses.

As diagrammatically illustrated at 112 in the drawing, path 1 has one impulse in each subgroup period; path 2 has two impulses in the first period and one in the second period; path 3 has three impulses in the first period and one in the second; path 4 has one impulse in the first and two in the second; path 5 has two in the first and two in the second; path 6 has three in the first and two in the second; path 7 has one in the first and three in the second; path 8 has two in the first and three in the second; and path 9 has three in the first period and three in the second. The marks X placed upon the nine conductor paths indicate interruptions, and the broken lines extending transversely of the paths indicate the division of the resulting impulses into groups and subgroups by the pick-up impulses. The classification which I have found it desirable to provide for in this embodiment of my invention is a division of the lines into three classes with respect to the character of the line; and into three classes with respect to the nature of the charge that is made for the use of the line. The lines are thus classified as individual, party line and private branch exchange or P. B. X. lines, and the classification of the lines with respect to the charge divides them into flat rate, message rate and coin collector lines. There are nine possible combinations

in this classification, for each of which combination there is a path through the identifying device which provides a characteristic identification for that class of line and service. Thus path 1 may have branches to and identify all the individual flat rate lines; path 2 in like manner may identify all of the party flat rate lines; path 3 may identify the private branch exchange flat rate lines; path 4, the individual message rate lines; path 5, the party message rate lines; path 6, the private branch exchange message rate lines; path 7, the individual coin collector lines; and path 8, the party coin collector lines. Path 9 would identify private branch exchange coin collector lines, if there were any such; but as it is not the practice to provide this class of service, path 9 is spare, in the present embodiment, and may be used for identifying some other class of service, if desired.

Of course, it will be understood that the scheme of identification outlined above is purely arbitrary and may be altered as desired to identify any other classes of service that may be provided. It will also be understood that by merely increasing the number of subgroups, or the number of impulses in each subgroup, or both, identification may be furnished for as many classes of service or as many line characteristics as may be desired.

When any line calls, it is extended, as shown in the present embodiment, by means of a line finder switch 200 and a cord finder switch 201 to a connecting cord circuit which terminates in a connecting plug 400 that is adapted to be inserted by the operator into any spring jack 401 in order to complete the connection between the calling and the called telephone lines. When the cord finder switch 201 finds the connecting cord circuit that is to be used in completing the connection, the calling line is automatically extended by way of the connecting cord circuit to the telephone set and controlling switches of the operator at whose position the selected connecting cord circuit is located.

Among the conductors of the connecting cord circuit that are extended to the associated operators' circuits when the connecting cord is selected, there are five, 500, 111, 502, 503 and 504 which are particularly concerned with the operation of the apparatus that has to do with the identification of the line with respect to its class of service. All five conductors lead to the class-of-service indicating device with which the operator is provided, conductor 502 being the wire over which the class-of-service indicating device starts a sequence switch 505, conductor 111 being the identifying wire of the line that is calling, conductor 500 being the wire over which the class-of-service re-

sponsive apparatus is brought into or out of action as the operators' circuits are connected with or disconnected from the connecting cord circuit, conductors 503 and 504 being the wires through which the class-of-service responsive device exercises control over the sort of current that is applied to the calling line by means of the operator's charge key. The sequence switch 505 is individual to an operator's cord circuit and controls in its contacts the operation of a sequence switch 402, and the relays associated with the operator's cord circuit for effecting the operations required for the class of the particular line calling.

The class-of-service responsive device to which the conductors 500, 502, 503, 504 and 111 lead, comprises in the present instance, six lamps arranged in two groups of three lamps each, and groups of relays for controlling the illumination of these lamps and for controlling the electrical condition of the two conductors 503 and 504 which have to do with the control of the operator's charge circuit. Before describing the circuits in detail, I shall outline briefly the manner in which the identifying device and the class-of-service responsive device coöperate to identify the extended line with respect to its class of service.

The extension of a calling line to a connecting cord, and thus to the associated operator, operates a relay 600, associated with the class-of-service responsive mechanism, which relay in its operation makes this mechanism responsive to subsequent identifying impulses. The identifying device continuously operates switch contacts which produce pick-up impulses, these impulses being of two sorts and having a definite time relation to the identifying impulses produced by the device. Pick-up impulse No. 1 is transmitted at the beginning of each cycle or train of identifying impulses, and pick-up impulse No. 2 is produced in the middle of each cycle to divide the group determined by consecutive pick-up impulses No. 1 into subgroups. For convenience and clearness in illustration, the commutator parts of the identifying device which produce the pick-up impulses are diagrammatically shown at 635 and 636 in Fig. 6 in connection with the class-of-service responsive mechanism at the operator's position.

In outline, the operation subsequent to the energization of the relay 600 is as follows: The first pick-up impulse No. 1 operates the relay 601 and extends the identifying conductor 111 to the relay 602. The termination of pick-up No. 1 impulse permits the relay 603 to operate, this relay acting to switch pick-up No. 1 circuit to relay 604, and pick-up No. 2 circuit to relay 605. The impulse of identifying current which flows

by way of conductor 111 as soon as relay 601 operates, operates relay 602, and this relay in turn causes the operation of relay 606. The first interruption in the identifying conductor 111, assuming that a second impulse is transmitted in the first subgroup period, causes the deenergization of relay 602 and the energization of relay 607, relay 606 remaining energized. When the circuit of the conductor 111 is again closed in this same subgroup period, relay 602 operates and brings about the operation of relay 608, and the subsequent interruption of the circuit leaves 608 up and operates 609 also, 609 in its operation deenergizing 606 and 607. If there is still another closure of the identifying conductor 111 in the first subgroup period, relay 602 is again operated, thus operating the relay 610, and upon the subsequent termination of the impulse, relay 611 is operated, and relay 610 remains up, relay 611 in its operation deenergizing relays 608 and 609. Thus, depending upon the number of impulses of current produced during the first subgroup period, relays 606 and 608, relays 608 and 609, or relays 610 and 611 of the group of impulse counting relays are left up, their locking circuit being by way of a conductor which is closed as long as relay 600 remains operated. Relay 606 of the first pair controls the circuit of lamp 612, which in the particular system of identification shown, is the individual line lamp; relay 608 of the second pair controls the circuit of lamp 613, which is the party line lamp; and relay 610 of the third pair controls lamp 614, which is the private branch exchange line lamp.

The first subgroup period is terminated by the production of pick-up impulse No. 2. Relay 603 having remained operated, this impulse causes the operation of relay 605, which relay, in turn, causes the operation of relay 615. Relay 605 opens the path of pick-up impulse No. 2 and locks itself up, subject to the control of relay 600; while relay 615 completes the circuit of the particular lamp 612, 613 or 614, which has been selected in the first subgroup period, and also gives relay 602 control over the group of counting relays 616, 617, 618, 619, 620 and 621. The impulses which are produced during the second subgroup period bring about the operation of the second group of counting relays 616, 617, 618, 619, 620 and 621, in the same way as described in connection with the operation of the first group of counting relays 606, 607, 608, 609, 610 and 611; that is, the first impulse causes the first pair of relays 616 and 617 to be left operated; the second impulse leaves the second pair of relays 618 and 619 operated; and the third impulse leaves the third pair of relays 620 and 621 operated, the locking circuit for whichever pair is left

operated being controlled in contacts of relay 600. Relay 616 of the first pair in the second group controls the circuit of lamp 622; relay 618 of the second pair controls 5 the circuit of lamp 623; and relay 620 of the third pair controls the circuit of the lamp 624. In the particular embodiment of my invention described, the lamp 622 is used 10 as the flat rate lamp, lamp 623 as the message rate lamp, and lamp 624 as the coin collector lamp.

The termination of the second subgroup, and, therefore, the termination of the cycle with respect to the train of identifying impulses, is brought about by the production 15 of another pick-up impulse No. 1. Inasmuch as relay 603 has remained energized, having a locking circuit by way of relay 600, the second pick-up impulse No. 1 flows 20 through relay 604, and the resultant operation of that relay opens the circuit of conductor 111 through relay 602, thus removing the class-of-service responsive mechanism from further control by the class-of-service identifying device over conductor 25 111. Relay 604, in operating, also closes a holding circuit for itself under the control of relay 600, and completes a circuit which causes the lighting of the particular lamp 30 622, 623 or 624, which has been selected, by the impulses during the second subgroup period. In its outer armature the relay 604 controls the movement of sequence switch 505 out of position 1 and into position 3. 35 Thus, the operation of the relay 600 causes the operator's class-of-service apparatus to be responsive to the identifying device during one cycle of its operation, during which cycle one of the lamps of the three in each 40 group is lighted to apprise the operator of the class of service of the calling line. As long as relay 600 remains operated, the associated responsive mechanism is maintained in its operated condition, and the lamps that 45 have been selected are kept lighted. When the relay 600 is deenergized, the responsive mechanism is restored to its normal condition, in readiness to register another indication whenever the relay 600 is again operated. 50

Associated with relays 618 and 620 of the second and third pairs, respectively, of the second group of relays, are two relays 625 and 626. These two relays control, through 55 the medium of the conductors 503 and 504, the circuits that are completed by means of the operator's charge key. Whenever relay 618 is operated, relay 625 is also operated to close the circuit of conductor 503, and 60 moves the sequence switch 505 out of position 3 and into position 5. Upon the actuation of a calling supervisory relay 403, this sequence switch is moved into position 6 and connects battery through a low resistance 65 relay 508, a branch of a conductor 509

through which the operator applies current to the third or sleeve conductor 110 of the line for the operation of the message register 209 of the line and the position register 510 of the operator's equipment. Whenever 70 relay 620 is operated, it causes the actuation of relay 626 which closes the circuit of conductor 504 to move the sequence switch 505 into position 7. Upon the energization of relay 403, the sequence switch is moved into 75 position 8 and connects a high voltage current generator 511 to conductor 512 to supply coin collecting current to the calling line, in case it be a line with a coin box, when the operator operates her charge key 80 405.

A type of device which may be employed for producing the identifying and pick-up impulses that serve to identify the various classes of lines is illustrated in Figs. 7, 8, 85 9 and 10. This device, in the form particularly illustrated, consists of ten cam-operated switches 627, 628, 629, 630, 631, 632, 633, 634, 635 and 636, each switch having an associated cam for operating it, the ten 90 associated cams being mounted upon a common shaft 637, which shaft is constantly driven by a suitable source of power. The shaft and associated cams may be driven to rotate at a rate of, say, 120 revolutions per 95 minute. Switches 627 to 634 inclusive are normally closed, and are operated by their associated cams to be opened momentarily once in each revolution. Switches 635 and 636 are normally opened, and are arranged 100 to be closed once in each revolution. The cams are cut away to produce the operation of their associated switches at any one of six points sixty degrees apart in the rotational cycle. These points or positions are 105 indicated by the Roman numerals I, II, III, IV, V, VI. The cams associated with switch springs 635 and 636 are cut away to produce the momentary closure of the switch contacts at positions I and IV, respectively, in 110 the cycle of rotation of the cam shaft. These switch springs are those which determine the pick-up impulses, switch 636 controlling pick-up impulse No. 1 and switch 635 controlling pick-up impulse No. 2. The 115 cams associated with switch springs 628, 630 and 633 are cut away at position II of the cycle; the cams associated with switch springs 627, 629 and 634 are cut away at position III of the cycle; the cam associated with the switch 631 is cut away at position V of the cycle; and the cam associated with switch 632 is cut away at position VI of the cycle. Thus the complete rotation of the cam shaft with its cams involves the 125 momentary closure of pick-up No. 2 switch 635 at position IV, the momentary opening of switch 631 at position V and the momentary opening of switch 632 at position VI.

The eight switches 627 to 634 inclusive 130

are connected in different combinations in the identifying paths 2 to 9 inclusive. Path 2 includes the contacts of switch 628; path 3 includes the contacts of switches 628 and 5 627; path 4 includes switch 631; path 5 includes switches 631 and 630; path 6 includes switches 631, 630 and 629; path 7 includes switches 631 and 632; path 8 includes switches 631, 632 and 633; and path 10 9 includes switches 631, 632, 633 and 634. Path 1 is adapted to remain closed in positions II, III, V and VI, and, therefore, does not include any of the switches that are operated in these positions.

15 The result of the above described arrangement of cam switches in the conducting paths of the identifying device is that these paths have produced in them the distinctive combinations of interruptions illustrated 20 diagrammatically at 112 in Fig. 1 of the drawing, the impulses produced by the interruptions being divided through the medium of the pick-up impulses Nos. 1 and 2 into groups and subgroups. The various 25 identifying device paths, thus adapted to produce trains of impulses divided into distinctive groups and subgroups, terminate upon connectors from which connection may be made with the fourth or identifying 30 conductor 111 of any line that it may be desired to identify, the connector to which the identifying conductor of the line is led depending upon the classification of the line with respect to whether it is an individual 35 line, a party line or a private branch exchange line, and whether it has a flat rate or a message rate, or is equipped with a coin box or collector.

Inasmuch as the present invention is not 40 particularly concerned with the character of the circuits over which the calling line is extended to the operator's position, and over which the calling line is extended to the called line after the operator has obtained 45 such identification of the calling line and such information concerning the called line as may be necessary for her purpose, these intermediate circuits and apparatus will be described only to the extent that they are 50 involved in the operation which has particularly to do with the disclosure of the invention. The organization chosen for the purpose of showing a specific embodiment of the invention is one which utilizes automatic finder switches for finding a calling 55 line and for extending the calling line to a connecting cord circuit that is at the time idle and available, and which utilizes a plug terminal for the connecting cord 60 circuit, which plug terminal is inserted by the operator into the spring jack of the wanted line. Such systems, with their automatic finder switches, sequence switches and control circuits, are well known, and this 65 specification need not be burdened with a

particular detailed description of such a system. An example of such a system is shown in the patent to Williams, No. 1,304-641, issued May 27, 1919.

In the operation of the particular embodiment of the invention illustrated, when one of the lines calls, the associated line relay 106, 107 or 108, as the case may be, is energized, and in closing its contacts closes a circuit which is effective, through intermediate circuits and apparatus that need not here be particularly described, in permitting current to flow, by way of conductor 202, through one winding of a relay 203 associated with the line and cord finder circuit. 70 This relay closes its contact 204 and completes a circuit by way of contacts 205 and 207 of a sequence switch 208 to cause the line finder switch 200 to connect with the terminals of the calling line. The sequence 80 switch 208 is adapted to rest in positions 1, 2, 3, 4, 6, 7, 8, 9, 14, 15, 16 and 17. Of these positions, the following are of interest in connection with this description:

- Position 1—Normal.
Position 2—Awaiting starting circuit.
Position 4—Hunting calling line.
Position 9—Hunting cord circuit.
Position 14—Talking.

It is not necessary to show the connection 90 of the circuit last traced with the motor magnet of the line finder switch, nor the path over which the finding of the calling line results in the sequence switch 208 being advanced through the intermediate stages 100 until it reaches position 9, which is the position in which the connecting cord circuit is hunted. The circuits for accomplishing this are well known in the art.

When the brush 211 of the line finder 105 200 comes into engagement with the corresponding terminal of the calling line, a circuit is completed that includes battery, resistance 213, sequence switch contact 214, brush 211 and its coöperating line contact, and the cut-off relay 103, 104 or 105 of the calling line. This energizes the cutoff relay and causes it to disconnect the associated line branch from the line.

When the sequence switch moves into position 9, the motor magnet of the cord finding switch 201 is made active, over circuits which need not be described, to cause the brushes 215, 216, 217 and 218 of the cord finder switch to engage corresponding contact terminals of an idle connecting cord. When the idle connecting cord is found, the sequence switch 208 is moved, by the closure of circuits that it is unnecessary to describe, into position 14, which is the talking position. In this position of the sequence switch the two talking conductors 219 and 220 of the finder circuit are connected through from brushes 209 and 210 of the line finder switch to brushes 215 and 216 of the cord 130

finder switch, by way of contacts 221 and 222 of the sequence switch, which contacts are closed in position 14. The third conductor 110 of the circuit is closed, in this 5 position, from brush 211 of the line finder switch to brush 217 of the cord finder switch by way of contact 214 of the sequence switch, one of the windings of relay 203 and contact 225 of the sequence switch. The 10 fourth or identifying conductor 111 is closed from brush 212 of the line finder switch to brush 218 of the cord finder switch by way of contact 207 of the sequence switch, contact 204 of relay 203 and contact 205 of the 15 sequence switch.

It will be noted that the motor magnet of the sequence switch, while the switch is resting in the talking position 14, is under the control of contact 228 of the relay by way 20 of contact 229 of the sequence switch closed in position 14; so that in the talking position relay 203 acts as a holding relay the deenergization of which causes the sequence switch to move to its next position.

25 The circuits of the connecting cord are governed by a sequence switch 402 which has five resting positions, as determined by a master contact 406, these resting positions being as follows:

30 Position 1—Normal.

Position 7—Listening-in.

Position 10—Ringing.

Position 15—Talking and listening-out.

Position 18—Release.

35 When the cord circuit is connected with by the cord finder switch 201, the sequence switch 402 is in its normal or No. 1 position. The engaging of brush 218 of the cord finder switch with the corresponding contact of the 40 idle cord circuit, advanced the sequence switch 208 of the finder circuit from its No. 9 or hunting position to its No. 14 or talking position by well-known circuits which need not be particularly illustrated or described

45 and as soon as sequence switch 208 leaves its No. 9 position, it completes a circuit which may be traced from ground through resistance coil 230, the right-hand contacts of sequence switch cam 225, brush 217 and its corresponding cord circuit contact, conductor 110, resting contact 407 of the charge key 405, conductor 408, the upper contact of sequence switch cam 514, conductor 515 and the winding of relay 409 to grounded battery.

55 The relay 409 becomes energized and closes a circuit from grounded battery through the primary winding of a repeating coil 410, the winding of an answering supervisory relay 411, the upper right-hand and lower left-

60 hand contact of sequence switch cam 413, the left-hand armature and front contact of relay 409, sequence switch cam 414, conductor 415, the winding of relay 300, conductor 301, the upper contact of sequence switch cam 416, the right-hand armature and front

contact of relay 409, the left-hand contacts of sequence switch cam 417, conductor 219 and the primary winding of the repeating coil 410 to ground. The relays 300 and 411 become energized and cause the connection 70 of the operator's telephone set 302 to the talking conductors 219 and 220. The relay 411 closes a circuit from ground through its armature and front contact, conductor 517, the lower contact of sequence switch cam 75 518, conductor 519, the lower contact of sequence switch cam 419, and the power magnet of sequence switch 402 to grounded battery, for moving the sequence switch 402 out of position 1 and into position 7. Thus 80 immediately upon the seizure of an idle cord, the operator may converse with the calling party.

While the sequence switch 402 is passing through position 1 $\frac{3}{4}$ and until it moves out 85 of position 8, a constantly rotating interrupter 424 is connected through the right-hand back contact and armature of relay 425, the upper contact of sequence switch cam 426, conductor 520, a lamp 521, and a 90 resistance 522 to grounded battery, causing the flashing of lamp 521 which indicates to the operator that a call is awaiting attention at her position. While the sequence switch 402 is moving from position 2 to 95 position 6, ground is connected, through the left-hand contacts of cam 430 and conductor 312 to the lower left-hand contacts of all the cams 419, the controlling sequence switches of which are in position 7. When 100 the sequence switch moves out of position 5, the above traced circuit for relays 411 and 300 is opened. These relays, however, are maintained energized and talking battery is supplied to the operator's and subscriber's 105 telephone sets from grounded battery through the primary winding of repeating coil 410, winding of relay 411, the conductor 220, the upper contacts of sequence switch cam 413, conductor 308, the inner front contact, armature and the winding of relay 300, conductor 301, the upper contacts of sequence switch cam 417, conductor 219, and the primary winding of the repeating coil 410 to ground. This circuit is maintained 110 closed until the sequence switch 402 moves out of position 8. When the sequence switch 402 reaches position 6 and until it moves out of position 8, the above traced path including contact of relay 409 and leading to the 115 operator's telephone set, is substituted by a path including the normal contacts of keys 303, 304 and 305, conductors 306 and 307 and sequence switch cam 420 and 421 for maintaining the connection between the operator's telephone set and the talking conductors 219 and 220.

The movement of the sequence switch 402 into position 7 brings the operator's receiving mechanism into association with the cir- 130

cuit. This is accomplished by the closure of a path from ground through sequence switch cam 427, conductor 500 and the winding of relay 600 to grounded battery, and the connection of conductor 111 through the left-hand contacts of cam 428 to the armature of relay 601. In response to the operation of relay 600 the class-of-service indicating apparatus is automatically caused to operate and thus the operator is apprised of the characteristics of the calling line with which the apparatus has just connected her. In response to the operation of relay 600, a path is closed over which the next pick-up 15 No. 1 impulse may operate the relay 601. This path is as follows: Ground, commutator switch 636, contact 638, back contact 639 of relay 603, and the winding of relay 601 to battery. When the first pick-up No. 1 impulse flows, after relay 600 is operated, relay 601 operates and closes a locking circuit for itself through its contact 640. When the contact 640 closes, a path is completed for the flow of current through the winding of relay 603 to ground, by way of contact 641 of relay 600. As long as the pick-up No. 1 impulse persists, no current flows through the winding of relay 603, because this path is short-circuited by the direct path from the winding of relay 601 to ground by way of the pick-up commutator 636. But the termination of the pick-up No. 1 impulse and the opening of the direct path to ground at 636, permit the current through the winding of relay 601 to be diverted into the path including the winding of relay 603 and contact 641 of relay 600. Thus, upon the termination of the first pick-up No. 1 impulse, relay 603 is operated, and thereafter relays 601 and 603 remain locked up as long as contact 641 of relay 600 remains closed. The opening of the back and closing of the front contact of relay 603 transfers the path through the pick-up No. 1 commutator 636 from relay 601 to the winding of relay 604 by way of normally closed contact 642 of the last mentioned relay. The closing of contact 643 of relay 603 connects the commutator switch 635 of pick-up No. 2 with the winding of relay 605 by way of normally closed contacts 644 of that relay. Relay 603 thus operates to make ready the paths over which the pick-up No. 2 impulse and the second pick-up No. 1 impulse subsequently operate to control the operation of the indicating device.

The actions described in the foregoing are those which follow immediately upon the extension of the calling line to the operator's circuit and the receipt of the first impulse from pick-up No. 1. The indicating apparatus is now in condition to receive the impulses of the first subgroup. The first impulse over conductor 111 after the operation of relay 601 flows by way of contact

645 of relay 601, through the winding of relay 602, and through the back contact and armature of relay 604 to ground. This impulse causes relay 602 to complete a circuit from battery through the winding of relay 606, the back contacts and armatures of relays 607, 611, 609, 607 and 615 and front contacts of relay 602 to ground. Relay 606, in operating, closes a locking path for itself to ground by way of the winding of relay 607, resting contact 646 of relay 609, and contact 641 of relay 600. The previously traced path from the winding of relay 606 to ground closes in the front contact of relay 602, short-circuits the path last traced; but at 80 the interruption in the flow of current which marks the end of the first impulse, relay 602 becomes deenergized, thus breaking the short-circuit path about relay 607 and causing that relay to operate. Thereafter relays 85 606 and 607 constituting the first pair of the selected relays, are held operated, subject to the control of the resting contact 646 of relay 609, and the contact 641 of relay 600. Relay 606 in its operated position closes a 90 path for the flow of current to the first lamp 612 of the first group of three lamps, subject to the control of normally open contact 647 of relay 615, which contacts are closed at a later stage of the operation by the passage 95 of the pick-up No. 2 impulse, as will hereinafter be described.

Relay 607, in operating, switches the circuit controlled by relay 602 from the winding of relay 606 to the winding of relay 608. 100 Therefore, the second impulse of current that flows over conductor 111 in the first subgroup period and operates relay 602, closes a path for the energization of relay 608 that may be traced from battery 105 through the winding of relay 608, front contact of relay 607, back contact of relay 615, and front contact of relay 602 to ground. The flow of current over this path operates relay 608, which relay closes 110 a locking circuit for itself by way of its front contact, the winding of relay 609, resting contact of relay 611 and contact 641 of relay 600 to ground. Current is diverted from the path last traced by the 115 short-circuit path completed by way of the back contact of relay 615 and the contact of relay 602. Upon the termination of the impulse this short-circuit path is interrupted and relay 609 is operated. Thereafter relays 608 and 609 are both held up, subject to the control of the back contact of relay 611 and contact 641 of relay 600. Relay 608, in operating, closes in its contact 120 a path for the subsequent flow of current through the second lamp 613 of the first group, under the control of contact 647 of relay 615, which is closed at a later stage 125 of the operation. Relay 609, in operating, breaks the locking circuit for the previously 130

operated pair of relays 606 and 607 and permits those relays to fall back. The falling back of relay 606 opens the circuit of lamp 612, so that that lamp will not be lighted 5 when contact 647 of relay 615 is subsequently closed; and relay 607 in falling back disconnects relay 608 from the controlling circuit and connects in its place relay 610 by way of the back contact of relay 607 10 and front contact of relay 609, which is one relay of the pair that is now energized.

The above described operation places relay 610 of the third pair in position to be energized by the closure of the front contacts of relay 602 resulting from a third impulse of current over the conductor 111. When relay 602 closes its contacts upon receipt of the third impulse, a path, like that previously traced for the operation of relay 20 606 and 608, is closed for relay 610 of the third pair; and relay 610 closes a locking circuit for itself through the winding of relay 611 and contact 641 of relay 600. Relay 611 is short-circuited and prevented from operating as long as the short-circuiting path by way of contact 647 of relay 615 and the contact of relay 602 is closed, in the manner previously described, and is operated as soon as the short-circuiting path is broken. Relay 610 in operating closes a path for the flow of current through the third lamp 614 of the first group, subject to the closure of the contact 647 of relay 615; and relay 611 in operating 30 opens the locking circuit for the previously operated pair of relays 608 and 609, and permits these relays to fall back and open the path prepared for the flow of current through the second lamp 613.

40 The first subgroup period is terminated by the production of pick-up No. 2 impulse by the momentary closure of contacts 635 of the commutator. It will be remembered that relay 603 had previously been locked up to prepare a path for the flow of the pick-up No. 2 impulse by way of the winding of relay 605. Upon the passage of the pick-up No. 2 impulse, relay 605 operates, closes a locking circuit for itself by way of its make contacts 45 644, subject to the control of contact 641 of relay 600, and also closes a circuit for relay 615. Relay 615, in operating, disconnects the circuit controlled by the contact of relay 602 from the path leading to the relays 606, 607, 608, 609, 610 and 611 of the first group, and connects it to the path which leads to the relays 616, 617, 618, 619, 620 and 621 of the second group. It also 50 closes the circuit for the flow of current over whichever of the lamps 612, 613 or 614 of the first group has its circuit left closed in the contacts of the associated relay 606, 608 or 610.

Assuming that three impulses of current

are caused to pass to the second group of 65 relays by way of the path controlled in the front contact 648 of relay 615, the selective operation of these relays by the successive impulses is the same as has been described in detail for the first group of relays, and 70 needs no further description. The only point which needs to be noted in connection with the action in the second group of relays, as distinguished from the action in the first group, is that relays 618 and 620 operating 75 do not prepare directly the circuits for the subsequent illumination of their associated lamps 623 and 624, respectively, but close the circuits of these lamps through the medium of the relays 625 and 626, which are operated when their associated relays 618 and 620, respectively, are operated, and which relays 625 and 626 also control circuits governing the operation of message 80 rate and coin collector apparatus, which circuits will be traced hereinafter.

The second subgroup period and the cycle are terminated by the production of a second pick-up No. 1 impulse in switch contacts 636 of the commutator. This impulse flows by 90 way of contact 638 of relay 600, front contact 649 of relay 603, resting contact 642 of relay 604, and through the winding of the last mentioned relay. Relay 604 is thus operated, closes a locking circuit for itself, 95 and completes a path for the illumination of whichever lamp 622, 623 or 624 of the second group is held in circuit by the energization of its associated relay 616, 618 or 620. Relay 604, in operating, also in opening its 100 back contact, opens the path for the flow of current through relay 602, so that that relay thereafter is unresponsive to the opening and closing of the identifying circuit associated with the calling line. The completion of the cycle or group period of the identifying device thus leaves the circuit of the identifying conductor 111 open in the back contact 650 of relay 604, the path of pick-up No. 1 impulse open in contacts 642 of relay 110 604, the path of pick-up No. 2 impulse open in contacts 644 of relay 605, and relays 601, 603, 604, 605 and 615 locked up subject to the control of contact 641 of relay 600. If it be assumed that there were three impulses 115 in each subgroup period, it also leaves relays 610 and 611 of the first group and relays 620 and 621 of the second group locked up over the locking circuit controlled in contact 641 of relay 600, and the associated 120 lamps 614 and 624 burning. It also, under the same assumption, leaves relay 626 held operated by the energization of relay 620, and the coin collector controlling path 504 closed to ground by way of the front contact of relay 604. This condition persists 125 and lamps 614 and 624 continue burning as long as relay 600 remains energized. When

that relay is deenergized the various locking circuits referred to are opened and the apparatus is restored to its normal position.

The actions described above were under 5 the assumption that each of the two sets of counting relays received three impulses in its respective subgroup period. I shall now describe briefly the action that would take place if only one or two impulses were received in a subgroup period. In such a case, the flow of current through identifying conductor 111, following the passage of the first pick-up No. 1 impulse acts, through the medium of the relay 602, to close the energizing circuit of the relay 606. But, assuming 10 that there is but a single impulse in the first subgroup period, this flow of current continues and the front contact of relay 602 is held closed throughout the whole of the 15 first subgroup period, and while this condition continues relay 607 is short-circuited and cannot pull up. The passage of the pick-up No. 2 impulse at the end of the first subgroup period actuates relays 605 and 615 20 as previously described, and relay 615, in operating, removes the short circuit from relay 607, and terminates the first subgroup period with relays 606 and 607 locked up and lamp 612 lighted. If there are assumed 25 to be two impulses in the first subgroup period, the opening of the contact of relay 602 marking the end of the first impulse removes the short circuit from relay 607 and permits it to operate; and relay 607, in operating, prepares the path for the energization 30 of relay 608 by the second impulse. Relay 609 of the second pair is kept short-circuited, as already described, during the passage of the second impulse; but the short 35 circuit is removed and relay 609 operates when pick-up No. 2 impulse operates relay 615 to open its resting contact at the end of the first subgroup period. In operating, relay 609 opens the locking circuit of 40 the first pair of relays 606 and 607, so that 45 two impulses during the first subgroup period leave the second pair of relays 608 and 609 locked up and their associated lamp 613 illuminated, and the other two pairs of 50 relays deenergized and their associated lamps dark.

The actions in the second group of counting relays, which follow the receipt of only one or two impulses in the second subgroup 55 period, are exactly the same as the actions described above as taking place in the relays of the first group. The result is that the lamp which is left lighted in each of the two groups corresponds with the number 60 of impulses which are received during that subgroup period, the operator being informed by the particular lamp lighted in the first group whether the calling line is an individual line, a party line or a private

branch exchange line, and by the particular 65 lamp lighted in the second group whether the line receives flat rate, message rate or coin collector service. Thus, when the operator's set 302 is automatically connected with the cord circuit to which the calling 70 line is extended and the relay 600 is operated, the class-of-service indicating apparatus is made operative to cause the calling line to indicate to the operator, by means of the particular lamps lighted, the class of 75 service for which the calling line is adapted. Thus informed, the operator is enabled to write such tickets or memoranda or give such service as her instructions require for 80 this sort of line.

Upon the energization of relay 604, a circuit is closed from ground through the right-hand outer armature and front contact of relay 604, conductor 502, contact 528 and the power magnet of sequence switch 85 505 to grounded battery. The sequence switch 505 is moved out of position 1 under the control of its master contact 529 into position 3. When the sequence switch 505 leaves position 2½, the above traced energizing circuit for relay 409 is opened in the upper contact of sequence switch cam 514, but this relay is maintained energized by current flowing from grounded battery through its winding, conductor 515, sequence 90 switch cam 530, conductor 531, the upper contact of sequence switch cam 453, conductor 464, resistance 462, the upper contact of sequence switch cam 455, and the lower back 95 contact and armature of relay 441 to ground. 100

In position 3 of sequence switch 505 and position 7 of sequence switch 402, the setting of sequence switch 505 is determined by the class-of-service indicator. Depending on the setting of the sequence switch 505, the 105 calling line will or will not be charged for the call. The controlling positions of this sequence switch are as follows:

- Position 1—Normal.
- Position 3—Flat-rate ringing.
- Position 4—Flat-rate talking.
- Position 5—Message flat-rate ringing.
- Position 6—Message flat-rate talking.
- Position 7—Coin collect ringing.
- Position 8—Coin collect talking.
- Position 9—Free call ringing.
- Position 10—Free call talking.

If neither the relay 625 nor the relay 626 is energized, then the sequence switch 505 remains in position 3.

If the relay 625 is energized, then a circuit is closed from ground through the left-hand armature and front contact of relay 604, the left-hand front contact and armature of relay 625, conductor 503, the left-hand contact of cam 543, conductor 544, sequence switch cam 431, conductor 545, and the power magnet of sequence switch 125

505 to grounded battery. Under the control of this circuit, the sequence switch 505 is driven out of position 3 and through position 4 into position 5.

5 If relay 626 was energized, instead of the last traced circuit, a circuit is closed from ground through the left-hand armature and front contact of relay 604, the right-hand front contact and armature of relay 626, 10 conductor 504, the lower right-hand contact of sequence switch cam 543, conductor 544, sequence switch cam 431, conductor 545, and the power magnet of sequence switch 505 to grounded battery. Under the control of 15 this circuit, the sequence switch 505 is driven out of position 3 and into position 7.

If under the control of relays 625 and 626 the sequence switch 505 was moved into position 5 or position 7 and the called line 20 is a free call line, *i. e.* one to which calls may be extended free of charge, the operator depresses key 546. The relay 547 becomes energized and locks up through conductor 548 and sequence switch cam 429. A 25 circuit is then closed from ground through the left-hand front contact and armature of relay 547, the upper contact of cam 543, conductor 544, cam 431, conductor 545, and the power magnet of sequence switch 505 to 30 grounded battery. The sequence switch 505 moves out of position 5 or 7 into position 9. When the operator inserts the plug 400 into the multiple jack 401 of the called line, a 35 circuit is closed from grounded battery, through the winding of relay 441, the sleeve contacts of plug 400 and jack 401, and the winding of the called line's cutoff relay 460 to ground.

The relay 441 opens in its back contact 40 the last traced energizing circuit of relay 409, this relay, however, remains locked up through a circuit extending from grounded battery, through the winding of relay 409, conductor 515, sequence switch cam 530, conductor 531, the upper contact of sequence switch cam 453, the left-hand front contact and armature of relay 409, the right-hand contacts of sequence switch cam 456, resistance 418, the left-hand back contact and armature of relay 435, the right-hand contact of sequence switch cam 430, conductor 310, the normal right-hand contacts of keys W, J, R and M in series to ground. The relay 441 closes a circuit from 55 ground through its lower armature and front contact, conductor 442, the lower left-hand contact of sequence switch cam 416, the right-hand front contact and armature of relay 409, the right-hand contacts of sequence switch cam 454, the right-hand armature and back contact of relay 450 and the winding of magnet 449 to grounded battery. The magnet 449 becomes energized and actuates an operator's position 60 meter which indicates the number of calls 65

handled through the particular operator's position. The magnet 449 closes also a circuit from ground, through its front contact and armature, lower left-hand contact of cam 419 and the power magnet of sequence 70 switch 402 to grounded battery. The sequence switch 402 moves out of position 7 and into position 10. The magnet 449 becomes deenergized. When the sequence switch moves out of position 8, the locking 75 circuit of relay 409 is opened in the upper right-hand contact of cam 456, and the operator's telephone set is disconnected from the connecting circuit.

As soon as the sequence switch moves out 80 of position 8, the lamp 521 is disconnected from the interrupter 424, and when the sequence switch 402 reaches position 9, the lamp is connected through the lower contact of cam 426, conductor 472, and the 85 lower contact of cam 538 to ground. The current flowing through this circuit causes the lamp to burn steadily which indicates to the operator that she may proceed to complete the desired connection as will be 90 hereinafter described. Upon the energization of the calling supervisory relay 403, the sequence switch is moved into some position in which the lower contact of cam 538 is open. For this reason, when the 95 called subscriber answers, the lamp 521 is extinguished.

A further result of the movement of sequence switch 402 out of position 7 is the deenergization of relay 600. This relay 100 opens in its left-hand front contact the locking circuits of all the energized relays of the class-of-service indicator, and restores this device to normal.

The means by which ringing current is 105 applied to the called line is of the well-known type of machine provided with various commutator segments. The commutator indicated at 465 is arranged to produce two rings within a certain period of 110 time and the commutator 466 is arranged to produce one ring within the set period of time. A commutator indicated at 467 is arranged to produce an impulse during the "silent" period of the ringing machine. 115 The production of an impulse during the silent period results in the energization of relay 452 by current flowing through the back contact and winding of relay 452 and the right-hand contacts of sequence switch 120 cam 459 to ground. The relay 452 becomes energized and locks up through its right-hand armature and front contact. In its left-hand front contact, the relay closes a circuit from ground through the left-hand 125 contacts of sequence switch cam 454, and the power magnet of sequence switch 402 to grounded battery to move the sequence switch out of position 10 and into position 15.

When the sequence switch leaves position 10 and opens the right-hand contact of cam 459, the relay 452 becomes deenergized. As soon as the sequence switch 402 reaches position 11, the following circuit is closed for controlling the ringing of the called party: from ground through the lower armature and front contact of relay 441, conductor 442, lower left-hand contact of sequence switch cam 443, the armature and back contact of the marginal ringing relay 444, the back contact and armature of the relay 445, the winding of relay 446, and resistance 447 to grounded battery. The relay 446 becomes energized. The relay 445 that is included in a parallel branch of this circuit cannot become energized because its winding is shunted through the path including the armatures and back contacts of relays 445 and 444. Upon the energization of relay 446, a ringing circuit is closed from ground through the back contact and inner armature of relay 434, the upper armatures and front contacts of relay 446 and relay 441, the tip contacts of plug 400 and jack 401, the bell at the called substation, the ring contacts of jack 401 and plug 400, the lower armature and front contact of relay 446, outer armature and back contact of relay 434, the winding of the marginal relay 444, the inner right-hand armature and back contact of relay 435 and the ringing commutator 466 to ground. Under the control of the commutator 466, the substation bell will be rung and when the called subscriber removes his receiver from the switchhook, the relay 444 becomes energized and thus by opening its back contact removes the shunt from the winding of relay 445. The relay 445 becomes energized, and closes through its right-hand armature and front contact, a shunt around the winding of relay 446, whereupon this relay becomes deenergized. Through a branch of the above traced ringing circuit extending through the left-hand back contact and armature of relay 445 and condenser 422 to conductor 219, a ringing tone is sent to the calling subscriber informing him that the called station is being signaled.

Upon the deenergization of relay 446, the calling supervisory relay 403 becomes energized and closes a circuit from ground, through its armature and front contact, conductor 542, the contacts of sequence switch cam 536, and the power magnet of sequence switch 505 to grounded battery. Depending on the setting of the sequence switch 505 under the control of the class-of-service indicator, this sequence switch moves now into positions 4, 6, 8 or 10. In any one of these positions of the sequence switch, a circuit is closed from ground, through the left-hand contact of cam 538, a calling supervisory lamp 549, and resistance 522 to grounded

battery. As long as the relay 403 is energized, the lamp 549 cannot light up because a shunt circuit exists through resistance 550, cam 541, conductor 542, and the front contact and armature of relay 403 to ground. 70

After the successful establishment of the connection the operator actuates the charge key 405. If the sequence switch 505 is standing in positions 4 or 10, a circuit is closed from grounded battery, through the 75 winding of relay 552, lower left-hand contact of sequence switch cam 551, conductor 509, contact 470 of the key 405, conductor 110 (Figs. 4, 2 and 1) and the windings of the calling subscriber's meter magnet 209 or 80 cut-off relay 103 or 104 to ground. Relay 552 becomes energized but in view of the relatively high resistance of the winding of this relay 552, the meter magnet 209 cannot become energized. Thus, if a line entitled 85 only to message rate service calls a free call line, the meter associated with such calling line will not register the call. The relay 552 causes the operation of magnet 510, which in turn operates a registering device 90 indicating the number of calls handled through the cord circuit shown in Fig. 5.

If the sequence switch is standing in position 6, the circuit for the calling subscriber's meter magnet extends through the 95 lower right-hand contact of sequence switch cam 551, and the winding of relay 508 to grounded battery. The winding of relay 508 is of relatively low resistance and for this reason both the relay 508 and the meter 100 magnet 209 become energized. The former operates the magnet 510, and the latter the calling subscriber's toll charging device.

In positions 7 to 8 of the sequence switch 505, the actuation of the charge key results in the closure of a circuit from ground, through a current generator 511, lamp 553, the winding of relay 554, cam 555, conductor 512, contact 471 of key 405, conductor 219, and then through a coin collecting magnet at the substation (not shown) to ground. The coin collecting magnet and the relay 554 become energized. The former causes the depositing of the coin in the coin box, and the latter lights the lamp 556 and thus 110 apprises the operator of the fact that the toll has been collected. If the call has been initiated from a pay-station and it becomes necessary to refund the coin, the operator depresses the key 305 and connects a generator of high voltage current 439 through a sequence switch contact 440, conductor 321, the make contact of key 305, conductor 306, sequence switch contact 420, conductor 219 and then to the magnet of 115 the coin box controlling the refunding of the coin. 120

When the calling and called subscribers restore their receivers to the switchhook, the supervisory relays 403 and 411 become 130

deenergized. These relays, by releasing their armatures permit the supervisory lamps 525 and 549 to light up. The operator, seeing the two supervisory lamps 5 lighted, removes the plug 400 from the jack 401, whereupon relays 441 and 460 become deenergized. The relay 441 opens the circuit of relay 445 and closes a circuit from ground through its lower armature 10 and back contact, the upper contact of cam 455, resistance 462, conductor 464, the upper contact of cam 453, conductor 531, cam 530, conductor 515, and the winding of relay 409 to grounded battery. Relay 409 becomes 15 energized and locks up through its left-hand front contact and armature, the lower contacts of cam 413 and resistance 463 to ground. A circuit is then closed from ground, through the right-hand contact of cam 416, the right-hand armature and front contact of relay 409, the lower contacts of cam 417, conductor 537, the lower contact of cam 536 and the power magnet of sequence switch 505 to grounded battery. The sequence switch 505 is moved out from the 20 position it was standing in, and into position 1. The lamps 521, 525 and 549 are extinguished and a circuit is closed from ground, through cam 532, conductor 533, the right-hand contacts of cam 428, and the 25 power magnet of sequence switch 402 to grounded battery. The sequence switch 402 is moved out of position 15 into position 18. The relay 409 becomes deenergized and 30 closes a circuit from ground, through the right-hand contact of cam 416, the right-hand armature and back contact of relay 409, the upper left-hand contact of cam 419, and the power magnet of sequence 35 switch 402 to grounded battery. The sequence switch 402 moves out of position 18 and into position 1.

While the sequence switch 505 was standing in some position between 2 and 11, the 40 relay 203 and the cutoff relay of the calling line were maintained energized by current flowing from grounded battery, through a resistance 557, the lower contact of cam 514, conductor 408, contact 407 of key 405, conductor 110, wiper 217, cam 225, the left-hand winding of relay 203, cam 214, wiper 211, conductor 110, and the winding of the cutoff relay to ground. When the sequence switch 505 is moved out of position 11, this 45 circuit is opened and the relays included therein become deenergized. The relay 203 closes a circuit from ground, through its contact 228, contact 229 and the power magnet of sequence switch 208 to grounded battery. The sequence switch 208 is moved out of position 14 into position 15, whereupon the switches 200 and 201 are restored to 50 normal.

If the signaling of a party line substa-

tion is desired, then, depending upon the 65 designation of the station, the operator depresses one of the keys W, J, R or M. Assuming that party W is called, the operator momentarily depresses the key W before inserting the plug 400 into the jack 401. In 70 order to insure the holding up of relay 409 while the key W is depressed, should the operator insert the plug 400 into the jack 401 during the time she has the key depressed, ground is supplied to the winding 75 of this relay through the right-hand normal contacts of keys M, R and J, the right-hand active contact of key W, conductor 322, the lower contact of cam 455, resistance 462 and conductor 464. The actuation of 80 the key W is without any result on the party line ringing control relays and for this reason the current is applied to the called line in the same manner as in the above assumed case, that is to say, one ring is applied to 85 the ringing side of the line. To indicate that the party W is being signaled, the lamp 323 is lighted by current flowing through a circuit extending from grounded battery through this lamp, the outer back contact 90 and armature of relay 315, the back contact and armature of relay 317, conductor 319 and sequence switch cam 437 to ground.

If the ringing of the party J is desired, the key J is momentarily depressed. Due 95 to the actuation of this key, a circuit is closed from ground through the left-hand resting contacts of keys M and R, the left-hand make contact of key J, conductor 313, the contact of sequence switch cam 432, the 100 windings of relays 433 and 434, resistance 457, conductor 535 and sequence switch cam 534 to grounded battery. The relays 433 and 434 become energized. When the keys M and W are in their normal position, the relay 409 is locked up in a circuit extending 105 from ground through the normal right-hand contacts of the party line ringing keys, conductor 310, upper right-hand contact of sequence switch cam 430, back contact and 110 left-hand armature of relay 435, resistance 418, right-hand contacts of sequence switch cam 456, left-hand armature and contact of relay 409, upper left-hand contact of sequence switch cam 453, sequence switch cam 115 530, conductor 515, winding of relay 409 to battery and ground. As far as the resistance 418 this circuit is parallel by a circuit extending from ground, the normal left-hand contacts of the party line ringing keys, conductor 324, upper left-hand contact of sequence switch cam 459, right-hand armature and back contact of relay 433 to resistance 120 418. If any one of the keys is depressed both of these grounds are removed, 125 but the relay 409 is held by the ground at the back contact of the lower armature of relay 441, or in case the plug 400 is inserted

in the jack 401 while any one of the keys is depressed, the relay 409 is held by a ground on conductor 322 as hereinbefore described. When the key J has been depressed and again restored, relay 433 is locked up and the holding ground, other than that supplied by the armature of relay 441, extends from ground through the right-hand normal contacts of the party line ringing keys, conductor 310, the upper right-hand contact of sequence switch cam 430, left-hand armature and back contact of relay 435 and thence over the circuit previously traced. Upon the insertion of the plug 400 into the multiple jack of the desired line, the relay 441 becomes energized and in turn causes the operation of magnet 449. The sequence switch is moved out of position 7 and into position 10. After the restoration of key J, the relays 433 and 434 are locked up through a circuit including the right-hand front contact and armature of relay 433, the left-hand contact of sequence switch cam 459, conductor 324, and the left-hand resting contacts of the party line ringing keys to ground. When the sequence switch moves out of position 8, a substitute ground is supplied for this locking circuit through the upper right-hand contact of cam 459. In response to the energization of relay 433, a circuit is closed from ground, through the left-hand armature and front contact of relay 433, sequence switch contact 468, conductor 316, and the winding of relay 317 to grounded battery. The relay 317 becomes energized and closes a circuit from grounded battery, through a lamp 325, the inner back contact and armature of relay 315, the front contact and armature of relay 317, conductor 319, and the sequence switch contact 437 to ground. The lighting of lamp 325 indicates to the operator that she has depressed the J key.

As above described, during a silent period of the ringing machine, relay 452 becomes energized and causes the movement of the sequence switch 402 out of position 10 and into position 15. The above-traced ringing circuit is now closed. However, in view of the fact that the relay 434 is energized, the commutator 466 of the ringing machine is connected to the tip strand 219 instead of the ring strand 220 of the cord circuit.

If the ringing of a party R is desired, the key R is momentarily depressed. A circuit is closed from ground, through the right-hand resting contact of key M, right-hand make contact of key R, conductor 326, the contact of sequence switch cam 436, the winding of relay 435, resistance 457, conductor 535 and sequence switch cam 534, to grounded battery. The relay 435 becomes energized and locks up through the upper right-hand contact of cam 430, conductor 310 and the right-hand resting contacts of

the keys. The relay 435 closes a circuit 65 from ground, through its right-hand outer armature and front contact, sequence switch cam 469, conductor 314 and the winding of relay 315 to grounded battery. The energization of relay 315 results in the establishment of a circuit from grounded battery, through lamp 318, the outer front contact and armature of relay 315, the back contact and armature of relay 317, conductor 319 and the sequence switch contact 437 to ground. The burning of the lamp 318 indicates to the operator that the party R has been selected. The relay 409 is maintained energized in the above described manner, the conductor 322 being grounded through the left-hand active contact of key R, and the locking circuit closed through the right-hand back contact of relay 433. In view of the fact that the relay 434 is deenergized, and the relay 435 is energized, when the sequence switch 402 moves into position 10, the commutator 465 is connected to the ring strand 220 for signaling the desired party line station.

If the key M is momentarily depressed, two circuits are closed, one circuit from ground, through the left-hand make contact of key M, conductor 313, sequence switch contact 432, the winding of relays 433 and 434; and the other circuit from ground through the right-hand make contact of key M, conductor 326, cam 436, the winding of relay 435; and then through resistance 457, conductor 535 and sequence switch contact 534 to grounded battery. Relays 433 and 435 become energized, when the sequence switch 402 moves into position 10, the ringing generator 465 is connected to the tip strand 219 for ringing the desired party line station. The relays 433, 434 and 435 are locked up in the above described manner. The locking circuit of relay 409 extends through the left-hand front contact and armature of the relay, the lower contact of cam 456 and then in series with the circuit including relays 433, 434 and 435.

The lamp lighted in response to the selection of the desired party line ringing current is extinguished when the sequence switch 402 moves out of position 7.

If for any reason the operator desires to listen in on a connection, she depresses the key 461 and thus closes a circuit through the upper right-hand contact of sequence switch cam 419 for driving the sequence switch 402 out of position 15 and into position 10. The sequence switch 402 is immediately driven out of position 18 and into position 1, the driving circuit being closed from ground, through the lower right-hand contact of cam 416, the right-hand armature and back contact of relay 409, the upper left-hand contact of cam 419 and the power magnet of se-

quence switch 402 to grounded battery. From this position, the sequence switch is driven into the listening-in position (7) by current flowing from grounded battery through the power magnet of the sequence switch, the lower right-hand contact of cam 419, conductor 519, and cam 538 to ground. The operator's telephone set 302 is now connected to conductors 219 and 220 through 10 the above described path.

In position 7 of the sequence switch 402, a circuit is closed from grounded battery through the winding of relay 425, the right-hand contacts of cam 443, the right-hand 15 back contact and armature of relay 409, the lower left-hand contact of cam 416, conductor 442, and the lower front contact and armature of relay 441 to ground. This circuit for relay 425 was not closed when the 20 sequence switch 402 moved into position 7 in response to the extension of the calling line to the operator's cord circuit, because at that time the relay 409 was energized. The relay 425 being energized, the interrupter 424 does 25 not cause the flashing of lamp 521 except for a short period of time, *i. e.* while the sequence switch 402 is passing through the positions in which the upper contact of cam 426 is closed. Thus in case the operator listens in 30 on a connection, she does not get the usual calling signal.

In view of the fact that the sequence switch 305 is now in some position 3 to 11, and the relay 441 is energized, no circuit is found for 35 the relay 409 when the sequence switch 402 moves into position 7 as a result of the actuation of the listening-in key 461. In response to the energization of relay 425, the relay 450 becomes energized and locks up through 40 its left-hand armature and front contact and the sequence switch contact 437.

When the operator desires to listen out again, she depresses the listening-out key 311, closing a circuit from ground, through 45 the contact of this key, conductor 312, the lower left-hand contact of cam 419, and the power magnet of sequence switch 402 to grounded battery. Under the control of this circuit, the sequence switch moves out 50 of position 7 and into position 10. The relays 425 and 450 become deenergized, and during the next silent period of the ringing machine, the relay 452 again operates to move the sequence switch 402 out of position 55 10 into position 15, which is the talking position.

If the operator desires to rering the called 60 substation, then instead of actuating her listening-out key, she removes the plug 400 from the jack 401 and reinserts it again. The relay 441 releases for a short time its armature. In its lower front contact, the relay 441 opens the locking circuit of relay 445, and in its lower back contact the relay 65 441 again closes an energizing circuit for

relay 409. The relay 409 becomes energized and locks up through some one of its above traced locking circuits. The relay 450 being energized, the operator's position meter 449 is not operated in response to the actuation 70 of relay 409. During the next silent period of the ringing machine a circuit is closed from ground through 467, the left-hand back contact and the winding of relay 451, the right-hand front contact and armature of 75 relay 450, the right-hand contacts of cam 454, the right-hand front contact and armature of relay 409, the lower left-hand contact of cam 416, conductor 442, and the front contact and armature of relay 441 to ground. The relay 451 becomes energized and locks up through its left-hand front contact and armature. A circuit is closed thereupon 80 from grounded battery, through the right-hand front contact and armature of relay 85 451, the lower contact of cam 453, conductor 531, cam 530, conductor 515 and the winding of relay 409 to grounded battery. The relay 409 is short-circuited and becomes deenergized. A ringing circuit is now closed from 90 grounded battery, through resistance 447, the winding of relay 446, the right-hand armatures and back contacts of relays 445 and 444, the upper contact of cam 443, the right-hand back contacts and armature of relay 95 409, the lower left-hand contact of cam 416, and the lower front contact and armature of relay 441 to ground. The ringing of the called 100 station is accomplished in the same manner as in the various assumed cases above described. When the called party answers, the operator depresses her listening-out key 311, whereupon the sequence switch moves out of position 7 and into position 15.

What is claimed is:

1. In a telephone exchange system, a plurality of calling lines, a called line, switching means for connecting any one of said calling lines to said called line, a sequence switch for controlling the operation of said switching means, and means for variably operating said switch depending on the line calling.

2. In a telephone exchange system, a plurality of calling lines of different character, 115 a called line, switching means for connecting any one of said calling lines to said called line, a switch, means depending on the character of the line calling for moving said switch into a plurality of operating positions, and means operable in the various positions of said switch for controlling the operation of said switching means.

3. In a telephone exchange system, a plurality of calling lines of different character, 125 a called line, switching means for connecting any one of said calling lines to said called line, a switch associated with said switching means, means depending on the character of the line calling for moving said 130

switch into a plurality of operating positions, and means controlled by said switch for operating said switching means.

4. In a telephone exchange system, a plurality of calling lines of different character, a called line, switching means for connecting any one of said calling lines to said called line, a switch for controlling the operation of said switching means, means for causing said switch to perform certain operations depending on the character of the line calling, means for causing said switch to perform certain other operations irrespective of the character of the line calling, and means for nullifying said certain operations of the switch.

5. In a telephone exchange system, a plurality of calling lines and a plurality of called lines of different character, switching means for connecting any one of said calling lines to any one of said called lines, a variably operable switch having a plurality of positions, means for causing said switch to move into a certain position depending on the character of the line calling, means for causing said switch to move into a certain other position depending on the character of the line called, and means operable in either one of said positions of said switch for controlling the operation of said switching means.

6. In a telephone exchange system, a plurality of lines, switching means for interconnecting two of said lines, an identifying device, means for operating said device depending on the character of the line calling, a switch movable into operating positions in response to the operation of said identifying device, and means actuated only in certain operating positions of said switch for controlling the operation of said switching means.

7. In a telephone exchange system, a plurality of lines, an operator's position, switching means thereat for interconnecting two of said lines, an identifying device, means for operating said device depending on the character of the line calling, a switch at said operator's position movable into operating position in response to the operation of said identifying device, and means actuated only in certain operating positions of said switch for controlling the operation of said switching means.

8. In a telephone exchange system, a plurality of lines, a plurality of trunk lines, means including a switching device for interconnecting two of said lines through one of said trunk lines, an identifying device, means for operating said device depending on the character of the line calling, a switch associated with each one of said trunk lines, means controlled by said identifying device for moving the switch associated with said one of said trunk lines into operating posi-

tions, and means controlled by said switch only in certain positions for controlling the operation of said switching means.

9. In a telephone exchange system, a plurality of lines, switching means having a normal resting position, means for operating said switching means for interconnecting two of said lines, an identifying device, means for operating said identifying device depending on the character of the line calling, a switch movable into operating positions in response to the operation of said identifying device, and means controlled only in certain operating positions of said switch for initiating the operation of said switching means.

10. In a telephone exchange system, a plurality of lines, switching means having a normal resting position, means for operating said switching means for interconnecting two of said lines, an identifying device, means for operating said identifying device depending on the character of the line calling, a switch movable into operating positions in response to the operation of said identifying device, and means controlled only in certain operating positions of said switch for returning said switching means to its normal resting position.

11. In a telephone exchange system, a plurality of lines, a switching means having a normal resting position, means for operating said switching means for interconnecting two lines, an identifying device, means for operating said identifying device depending on the character of the line calling, a switch movable into operating positions in response to the operation of said identifying device, and means controlled only in certain positions of said switch for initiating the operation of and returning to normal said switching means.

12. In a telephone exchange system, a plurality of lines, an operator's position, switching means at said operator's position for interconnecting two lines, call supervising means at said operator's position, an identifying device, means for operating said identifying device depending upon the character of the line calling, a switch movable into operating positions in response to the operation of said identifying device, and means controlled only in certain operating positions of said switch for controlling the operation of said supervising means.

13. In a telephone exchange system, a plurality of lines, an operator's position, means for extending a calling line to said operator's position, switching means at said operator's position for further extending the calling line to a called line, an identifying device, means for operating said identifying device depending on the character of the line calling, a switch movable into certain operating positions in response to the opera-

tion of said identifying device, a calling line signal at said operator's position, and means controlled only in a certain operating position of said switch for controlling the operation of said calling line signal.

14. In a telephone exchange system, a plurality of lines, means for interconnecting calling and called lines, an identifying device, means for operating said identifying device depending on the character of the line calling, a switch movable into operating positions in response to the operation of said identifying device, means for signaling called lines, and means controlled only in certain positions of said switch for controlling the operation of said last mentioned means.

15. In a telephone exchange system, a plurality of lines, switching means for interconnecting calling and called lines, an identifying device, means for operating said identifying device depending on the character of the line calling, a switch movable into operating positions in response to the operation of said identifying device, means associated with said switching means to signal interconnected lines, and means controlled only in certain operating positions of said switch for controlling the operation of said last mentioned means.

16. In a telephone exchange system, a plurality of lines, switching means for interconnecting calling and called lines, an identifying device, means for operating said identifying device depending on the character of the line calling, a switch responsive to the operation of said identifying device, a source of signaling current, means operative in response to the operation of said switching means for repeatedly applying said source of current to the called line, means for reapplying said source of current to said called line, and means controlled by said switch for controlling the operation of said last two mentioned means.

17. In a telephone exchange system, a plurality of lines, switching means for interconnecting calling and called lines, an identifying device, means for operating said identifying device depending on the character of the line calling, a switch responsive

to the operation of said identifying device, a source of ringing current associated with said switching means, means actuated in response to the operation of said switching means for repeatedly applying said source of current to the called line, means for re-ringing the called line, and means controlled by said switch for controlling the operation of said last two mentioned means.

18. In a telephone exchange system, a plurality of lines, switching means for establishing a connection between a calling and a called line, an identifying device, means for operating said identifying device depending on the character of the line calling, a switch movable into operating positions in response to the operation of said identifying device, means for severing said connection, and means controlled only in certain positions of said switch for controlling the operation of said last mentioned means.

19. In a telephone exchange system, a plurality of lines, an operator's position comprising switching means and an operator's telephone set, means including said switching means for interconnecting two lines, an identifying device, means for operating said identifying device depending on the character of the line calling, a switch movable into operating positions in response to the operation of said identifying device, and means controlled only in a certain position of said switch for connecting said operator's telephone set to said calling line.

20. In a telephone exchange system, a plurality of lines, an operator's position comprising switching means and an operator's telephone set, means including said switching means for interconnecting two lines, an identifying device, means for operating said identifying device depending on the character of the line calling, a switch responsive to the operation of said identifying device, and means controlled by said switch for connecting the operator's telephone set with said interconnected lines.

In witness whereof I hereunto subscribe my name this 14th day of May, A. D. 1918.

ALBEN E. LUNDELL.
